UNITED STATES PATENT OFFICE.

MOSES J. POWELL, OF BRIDGEPORT, ILLINOIS.

ENGINE-STARTING DEVICE.

Application filed May 4, 1925. Serial No. 27,977.

This invention relates to certain new and useful improvements in engine starting devices, and has more particular reference to a safety starting device for internal combustion engines.

The primary object of the invention is to provide a mechanical safety starting device for internal combustion engines, by means of which liability of personal injury, 10 such as the spraining of arms etc., due to back firing of the engine caused by too early ignition of the explosive mixture, is eliminated.

Another object of the invention is to provide a safety starting device of the above kind which is extremely simple and durable in construction as well as efficient in operation.

With the above general objects in view, 20 and others that will become apparent as the nature of the invention is better understood, the same consists in the novel form, combination and arrangement of parts herein-after more fully described, shown in the accompanying drawings and claimed.

In the drawings, wherein like reference characters indicate corresponding parts throughout the several views,

Figure 1 is a fragmentary view, partly in 20 side elevation, and partly in central longitudinal section, of a starting device constructed in accordance with the present invention,

Figure 2 is an end view looking toward 35 the right of Figure 1, with parts removed to reveal other parts,

Figure 3 is a transverse sectional view taken substantially upon line 3—3 of Figure 1,

Figure 4 is a fragmentary sectional view 40 taken substantially upon line 4—4 of Figure 2,

Figure 5 is a view similar to Figure 4 taken substantially upon line 5—5 of Figure 2, and

Figure 6 is an enlarged perspective view of one of the pawls.

Referring more in detail to the drawings, the invention is herein shown as embodying 50 a hand crank having a shank portion composed of an inner section 5 and an outer section 6 connected in end to end relation by a safety device generally indicated at 7, the usual clutch element 8 being secured 55 on the inner end of the inner shank sec-

tion 5 for engagement with the usual well known cooperating clutch element on the engine crank shaft whereby turning movement of the hand crank may be imparted to said crank shaft for starting the engine. 60 The hand crank further embodies a handle portion 9 whose inner end is rigidly connected to the outer end of the outer shank section 6 by means of a transversely extending connecting portion 10 whereby the 65 portions 6 and 9 are laterally offset relative to each other and extend in parallel relation but in opposite direction from the portion 10.

The safety device 7 essentially embodies 70 means including pawls 11 for freely permitting rotation of the outer shank section 6 in one direction and for positively preventing rotation thereof in the other direction, and means including a fragile element 75 12 connecting the shank sections 5 and 6 whereby the rotation of section 6 in said one direction will be imparted to section 5 for starting the engine and whereby the section 5 may be forcibly rotated in the 80 said other direction, due to back firing of the engine, while the section 6 is held against rotation in said other direction by said rotation preventing means, so as to prevent injury to the user of the hand crank. The 85 safety device also includes a support 13 for the pawls 11 of the rotation preventing means, and means including a guide 14 to restrain said support from rotation and to permit movement of the hand crank bodily 90 toward and away from the engine, whereby the crank may be engaged with or disengaged from the engine crank shaft.

The support 13 is preferably in the form of a cylindrical casing having a removable 95 inner end wall 15 and a rigid outer end wall 16, a pair of depending external lugs 17 being rigid with the lower part of the casing 13 and disposed in spaced side by side relation to slidably receive the guide strip 14 100 therebetween, and the inner end of said guide strip being adapted to be rigidly secured to a fixed support, such as a vehicle or engine frame, not shown.

The means for connecting the shank sections 5 and 6 preferably embodies three disks 18, 19 and 20 disposed within the casing 13 in side by side contiguous relation, the disk 20 having peripheral ratchet teeth 21 engaged by the pawls 11 which are pref- 110

erably pivoted in recesses 22 of the casing 13 and yieldingly pressed inwardly to engage the teeth 21 by means of springs 23.

The disks 19 and 20 have hubs 24 and 25 respectively journaled in the end walls 15 and 16 of the casing 13, and the disk 18 is journaled on the hub 24 of the disk 19. The outer end of the inner shank section 5 is secured in the hub 24 so that this shank section and the disk 19 operate as though integral parts.

The disks 18, 19 and 20 have marginal perforations or openings 26, and a circular series of these openings is preferably provided in each disk so that an opening of one disk may be more readily brought into registry with openings of the other disks for reception of the fragile element 12. This fragile element is preferably in the form of a wooden pin capable of functioning in the desired manner and adapted to be sheared when the disk 19 is caused to rotate by back firing of the engine and the pawls 11 act to prevent rotation of disk 20. The end walls of the casing 13 have aligned openings 27 with which the openings of the disks are adapted to be aligned for permitting insertion of a fragile pin or removal of a broken pin.

30 When the invention is in the nature of a hand crank, the inner end of the outer shank section 6 is preferably of polygonal cross section and removably fitted in the similarly shaped bore of the hub 25. However, any suitable means may be provided for facilitating manual rotation of the shank section 6.

From the foregoing description it is believed that the construction and operation 40 as well as the advantages of the present invention will be readily understood and appreciated by those skilled in the art. It is noted that the pawls 11 are so arranged as to separately and consecutively engage the teeth 21 so that their operation is much more effective.

The disk 20 is provided with a circular series of rigid laterally projecting splines 28 which extend rearwardly past the periphery 50 of the intermediate disk 19 and engage in peripheral recesses 29 of the inner disk 18. This permits rotation of disk 19 relative to the disks 18 and 20 and insures rotation of disks 18 and 20 in unison, whereby the intermediate part of the fragile pin 12 is sheared from the end portions thereof when the engine back fires.

Minor changes may be made without departing from the spirit and scope of the invention as claimed.

What I claim as new is:

1. A safety engine starting device including a shank composed of an inner section and an outer section arranged in end to end 65 relation, a clutch element upon the inner end

of the inner shank section, means for facilitating manual turning of the outer shank section, and a safety device connecting the adjacent ends of said shank sections, said safety device including a fragile connecting element, and means including pawls for freely permitting rotation of the outer crank section in one direction and for positively preventing rotation thereof in the other direction, a support for said pawls, and means including a guide to restrain said support from rotation and to permit movement of the starting device bodily in a direction parallel with the longitudinal axis of the shank.

2. A safety engine starting device comprising a casing, a plurality of disks journaled within the casing in side by side contiguous relation, one of said disks being provided with peripheral ratchet teeth, spring pressed pawls carried by the casing and engaging said ratchet teeth, means for preventing rotation of the casing, a fragile connecting element between said disks, a pair of aligned shank sections having adjacent ends respectively engaged with the disks to rotate therewith, means upon the inner end of the inner shank section for engagement with an engine crank shaft, and means for facilitating manual rotation of the outer shank section.

3. A safety engine starting device comprising a casing, a plurality of disks journaled within the casing in side by side contiguous relation, one of said disks being provided with peripheral ratchet teeth, spring pressed pawls carried by the casing and engaging said ratchet teeth, means for preventing rotation of the casing, a fragile connecting element between said disks, a pair of aligned shank sections having adjacent ends respectively engaged with the disks to rotate therewith, means upon the inner ends of the inner shank section for engagement with an engine crank shaft, and means for facilitating manual rotation of the outer shank section, said fragile connection comprising a fragile pin, said disks having a circular series of marginal openings adapted to be selectively registered for reception of said fragile pin.

4. A safety engine starting device comprising a casing, a plurality of disks journaled within the casing in side by side contiguous relation, one of said disks being provided with peripheral ratchet teeth, spring pressed pawls carried by the casing and engaging said ratchet teeth, means for preventing rotation of the casing, a fragile connecting element between said disks, a pair of aligned shank sections having adjacent ends respectively engaged with the disks to rotate therewith, means upon the inner end of the inner shank section for engagement with an engine crank shaft, and means for facilitating manual rotation of the outer shank section.

the outer shank section, said fragile connection comprising a fragile pin, said disks having a circular series of marginal openings adapted to be selectively registered for 5 reception of said fragile pin, said first named disks having hub portions for reception of said shank sections a third disk journaled upon the hub of one of said first named disks, and lateral marginal splines 10 rigid with the other of said first named disks, said third named disk having marginal recesses in which said splines are fitted.

5. A safety engine starting device including a shank composed of an inner section and an outer section, a safety device connecting said shank sections in end to end re-

lation and including a fragile connecting element, a casing for said safety device, pawl and ratchet means for preventing rotation of the casing outer shank section in 20 one direction and including pawls carried by the casing, a clutch element upon the inner end of the inner shank section, means for facilitating turning of the outer shank section, and means for preventing rotation 25 of said casing and for permitting movement of the starting device bodily in a direction parallel with the longitudinal axis of said shank.

In testimony whereof I affix my signature.

MOSES J. POWELL.
